(57) **CLAIM**

The ornamental design for a nozzle for plasma torch, as shown and described.

DESCRIPTION

FIG. 1 is a front view of our nozzle for a plasma torch showing our design. The broken line showing of the nozzle in FIGS. 1, 2, 4 and 5 is for illustrative purposes only and forms no part of the claimed design.

FIG. 2 is a plan view of our nozzle;

FIG. 3 is a right side view of our nozzle;

FIG. 4 is a left side view of our nozzle; and,

FIG. 5 is a cross sectional view, taken along line 5 —5 of FIG. 1 .
